UNITED STATES PATENT OFFICE.

WALTER V. TURNER, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

STEAM-DRIVEN COMPRESSOR.

1,176,109.

Specification of Letters Patent. Patented Mar. 21, 1916.

Application filed January 19, 1915. Serial No. 3,052.

To all whom it may concern:

Be it known that I, WALTER V. TURNER, a citizen of the United States, residing at Edgewood, in the county of Allegheny and State of Pennsylvania, have invented new and useful Improvements in Steam-Driven Compressors, of which the following is a specification.

This invention relates to fluid compressors, and more particularly to a compound steam pumping engine of the type having the pump pistons directly connected to the steam pistons, such as those covered in the prior Patents, No. 441,209 of Geo. Westinghouse, dated November 25, 1890, and No. 965,578 of A. England, dated July 26, 1910. With this type of compressor, various conditions of leakage may interfere with the proper action thereof, such as leakage of steam past the high or low pressure steam pistons, leakage of fluid around the high or low pressure air pistons, and leakages at the discharge valves or intermediate valves. Such leakages tend to prevent the full and simultaneous stroking of the steam and pump pistons and the effectiveness of the compressor is thus impaired by failure to operate at maximum efficiency, stalling of the compressor, inability to operate under the desired maximum air pressure, and the like.

The principal object of my invention is to provide means for insuring the prompt, full, and simultaneous stroking of the steam and pump pistons of a compound compressor.

In the accompanying drawings; Figure 1 is a central vertical section of a compound fluid compressor embodying my improvements and showing the position of the parts with the high pressure steam piston moving upwardly; Fig. 2 a similar view, with the high pressure steam piston moving downwardly; Fig. 3 a central vertical section of a compound fluid compressor embodying a slightly modified form of my invention, showing the parts in position when the high pressure steam piston is moving upwardly; and Fig. 4 a similar view, when the high pressure steam piston is moving downwardly.

The compressor may comprise a valve section 1, steam cylinder casing 2, air cylinder casing 3 and a section 4 intermediate the steam and air cylinder casings. In the high

pressure steam cylinder 5 is a steam piston 6 connected by piston rod 7 with air piston 8 contained in air cylinder 9, and the low pressure steam cylinder 10 contains steam piston 11 connected by piston rod 12 with air piston 13 contained in air cylinder 14 and in accordance with one feature of my invention, the high pressure air piston is connected to the high pressure steam piston while the low pressure steam piston is connected to the low pressure air piston. The low pressure air cylinder 14 is provided with the usual fluid inlet valves 15 and 16 and intermediate valves 17, 18, 19, and 20 for controlling the flow of compressed fluid from the low pressure cylinder 14 to the high pressure cylinder 9. The high pressure cylinder is also provided with the usual discharge valves 21 and 22. Mounted in a piston chamber of the valve section 1 is a main steam distribution valve of the valve piston type and having differential piston heads 23 and 24 with intermediate piston valves 25, 26, and 27 for controlling the admission and exhaust of steam to and from the steam cylinders.

For effecting the operation of the main steam valve, two reversing valves 28 and 29 are provided, the valve 28 being operated by the movement of the low pressure steam piston 11 and the valve 29 by the movement of the high pressure steam piston 6. Assuming the parts in the positions shown in Fig. 1 of the drawings, steam admitted through pipe 30 to the compressor flows through passage 31 to the space between piston heads 24 and 25 and thence through passage 32 to the piston chamber at the under side of high pressure steam piston 6, causing the upward movement of said piston. The piston chamber above the high pressure piston 6 is connected to the piston chamber above low pressure steam piston 11 through passage 33, space intermediate the piston valves 26 and 27, and passage 34, so that the exhaust steam from the high pressure steam piston is supplied to the piston 11 for driving the same downwardly. As the high pressure steam piston 6 moves to the end of its upward stroke, the striker plate 35 engages the shoulder 36 of the reversing rod 37 and the valve 29 is thus shifted to the position shown in Fig. 2.

The controlling ports for the main steam valve are so arranged that movement of both

reversing valves 28 and 29 is required to effect the shifting of same and therefore no action takes place until the low pressure steam piston moves to the end of its downward stroke, when the engagement of the striker plate 38 with the button on the end of the reversing rod 39 operates to shift the valve 28 downwardly to the position shown in Fig. 2 of the drawings. With both reversing valves in the positions shown in Fig. 2, the valve chamber 40, open through passage 41 to the steam supply pipe 30, is connected by port 42, passage 43, cavity 44 in valve 28 and passage 45 with the chamber 15 adjacent to piston head 23. The smaller piston head 24 being constantly subject to atmospheric pressure, the unbalanced steam pressure on the piston head 23 effects the movement of the main steam valve to the 20 right as shown in Fig. 2 and in this position, steam is admitted to the piston chamber above piston 6 from the space between piston heads 23 and 27 and through passage 33. Exhaust steam from the piston 25 chamber below piston 6 is also admitted to the under side of low pressure piston 11 through passage 32, space between piston heads 25 and 26, and passage 47. The high pressure steam piston is thus caused to move 30 downwardly and the low pressure piston 11 upwardly. As the steam pistons approach the end of their respective strokes, the reversing valves 28 and 29 are shifted and when both have been shifted the valves will 35 be in the positions shown in Fig. 1, in which the chamber at the face of piston head 23 is connected to the exhaust through passage 48, cavity 49 in reversing valve 28, passage 50, cavity 51 in reversing valve 29, and passage 52 which opens to steam exhaust port 53. As the piston head 23 is of greater area 40 than piston head 24, there will be an unbalanced pressure head acting on the inner face of piston 23 which operates to shift 45 the main steam valve to the position shown in Fig. 1. Steam will now be exhausted from the piston chamber below the low pressure piston 11 to the atmosphere through passage 47, space between piston 50 heads 25 and 26 to exhaust port 53, steam being admitted to operate the high and low 55 pressure steam pistons as hereinbefore described.

The above operation assumes that the high and low pressure pistons reach the ends of their respective strokes simultaneously, as they are normally intended to operate. If, however, the low pressure steam piston should reach the end of its downward 60 stroke before the high pressure piston makes its upward stroke, as may occur, for example, when leakage around the high pressure steam piston causes an excessive back pressure thereon, then only the reversing valve 28 will be shifted, but this oper-

ates to connect the back pressure side of the high pressure steam piston and also the lower side of the low pressure piston to the exhaust through passage 33, passage 54, cavity 55 in reversing valve 29, passage 56, cavity 57 in reversing valve 28, passage 58, passage 47, and space between piston heads 25 and 26 to exhaust port 53. The low pressure piston having completed its stroke, the sooner the exhaust steam is exhausted, 75 the better, while the exhaust of steam from the upper face of high pressure piston 6 directly to the atmosphere operates to facilitate the prompt movement of the high pressure piston to the end of its stroke by 80 freeing the same of back pressure. This prevents stalling and tends to bring about the more nearly simultaneous action of the steam pistons. If the low pressure piston 11 completes its upward stroke before the 85 high pressure piston 6 finishes its down stroke, the reversing valve 28 will be shifted upwardly so as to connect the under side of the high pressure piston with the direct exhaust through passage 32, passage 59, cavity 90 60 in reversing valve 29, passage 61, cavity 62 in reversing valve 28, passage 63, exhaust side of low pressure piston 11, passage 34, and space between piston heads 26 and 27. On the other hand, should the high pressure 95 steam piston reach the end of its stroke first, means are provided for admitting live steam to the acting side of the low pressure piston. If the high pressure piston makes its upward stroke first the reversing valve 100 29 is shifted upwardly and operates to supply live steam to the piston chamber at the upper face of low pressure steam piston 11 from passage 32 through passage 59, cavity 60 in reversing valve 29, passage 61, cavity 105 62 in reversing valve 28, and passage 63. Live steam thus supplied to the low pressure piston assists the movement thereof and tends to make the strokes of the high and low pressure pistons more nearly simultaneous. In a similar manner, if the high pressure steam piston 6 completes its downward stroke in advance of the completion of the upward stroke of the low pressure piston, then the reversing valve 29 is shifted 110 115 downwardly and live steam is admitted to the piston chamber below the low pressure piston 11 from space between piston heads 23 and 27, through passage 33, passage 54, cavity 55 in valve 29, passage 56, cavity 57 in valve 28, passage 58, and passage 47. Although the downward movement of the reversing valve 29 cuts off port 42 which supplies steam to piston 23, the steam pressure on said piston is still maintained by steam supplied through passage 75, cavity 76 in valve 29, passage 43, cavity 44, and passage 45.

It will now be seen that means are provided for insuring the full stroke of both 120 125 130

the high and the low pressure steam pistons, since the movement of the low pressure steam piston to the end of its stroke before the high pressure steam piston finishes its 5 stroke causes the opening of communication for relieving the back pressure on the high pressure steam piston, while the movement of the high pressure steam piston ahead of the low pressure steam piston effects the admission of live steam to the operating side 10 of the low pressure steam piston.

While in the drawings, the low pressure steam piston is connected with the low pressure pump piston and the high pressure 15 steam piston with the high pressure pump piston, if desired, the pistons may be cross connected, as shown in Patent No. 965,573, hereinbefore referred to.

In Figs. 3 and 4 of the drawings a slightly 20 modified construction is shown, the manner of supplying live steam to the low pressure steam piston and exhausting steam therefrom being somewhat different from that of the construction shown in Figs. 1 and 2 of 25 the drawings.

In the operation of the modified construction, when the compressor is not running, the high and low pressure steam pistons will be at the bottom of the respective cylinders 30 with the reversing valves 28' and 29' in their lower positions. If steam is admitted to the compressor, it will flow to the face of piston 23 from valve chamber 60, through port 61 and passage 45', and the chamber 35 at the outer face of piston 24 being at atmospheric pressure, the steam distribution valve will be moved to the position shown in Fig. 4. Steam can then flow to the high pressure steam cylinder above the piston 6 40 through passage 31, space between piston heads 23 and 27, and passage 33. Steam also flows to the low pressure steam cylinder below piston 11 through passage 41, valve chamber 40', passage 63, cavity 64 in reversing 45 valve 28', passage 65, and passage 47. The low pressure steam piston will thus be forced upwardly by live steam, while air will be drawn into the air cylinder below piston 13 through inlet valve 16. As the 50 low pressure steam piston reaches the end of its upward stroke, the reversing plate 38 operates the reversing valve 28', moving same to the position shown in Fig. 3. This movement blanks the passage 45' and at the 55 same time cavity 66 connects passages 54' and 67. The outer face of piston head 23 is then open to the exhaust through passage 68, cavity 69 in reversing valve 29', passages 70 and 67, cavity 66, and passage 54'. Since 60 the space at the outer face of piston head 24 is also subject to atmospheric pressure, the unbalanced pressure acting on the inner face of piston head 23 operates to shift the steam distribution valve to the position 65 shown in Fig. 3. Live steam is now sup-

plied to the underside of the high pressure steam piston 6 from the space between piston heads 24 and 25 and through passage 32, thus forcing this piston upward. Exhaust steam from above piston 6 will now 70 expand into the low pressure steam cylinder above piston 11 through passage 33, space between piston heads 26 and 27, and passage 34, thus forcing the low pressure piston downward, the lower side of piston 11 being 75 open to the exhaust port 53, through passage 47 and space between piston heads 25 and 26. The low pressure air piston now 80 operates to draw in air from the atmosphere through inlet valve 15 and air compressed below the piston passes the intermediate valves 19 and 20 into the high pressure air cylinder below piston 8. When the high pressure steam piston 6 completes its upward stroke, the reversing valve 29' is 85 shifted upwardly while the movement of the low pressure steam piston downwardly operates to shift the reversing valve 28' to its lower position, as shown in Fig. 4. The steam distribution valve is now shifted to 90 the right by the admission of steam to the face of piston head 23, so that live steam is supplied to the upper side of piston 6 and exhaust steam from the under side of said piston is admitted to the under side of 95 the low pressure steam piston 11, operating the pistons to compress air as before described. If the high pressure steam piston 6 should complete its downward stroke first, the reversing valve 29' will be moved to its 100 lower position and live steam will be admitted to the under side of the low pressure piston 11 from reversing valve chamber 40' through passage 63, cavity 64 in reversing valve 28', passage 65, and passage 47. Similarly, if the high pressure piston completes 105 its upward stroke first, live steam will be admitted to the upper side of the low pressure piston from valve chamber 40' through passage 71, cavity 72 in reversing valve 28', 110 passage 73, and passage 34.

Having now described my invention, what I claim as new and desire to secure by Letters Patent, is:

1. In a compound pumping engine, the combination with a high pressure engine cylinder and piston and a low pressure engine cylinder and piston, of means controlled by the high pressure piston for supplying live steam to the low pressure piston. 115

2. In a compound pumping engine, the combination with a high pressure engine cylinder and piston and a low pressure engine cylinder and piston, of means operated upon movement of the high pressure piston to the 125 end of its stroke ahead of the low pressure piston for supplying live steam to the low pressure piston.

3. In a compound pumping engine, the combination with a high pressure engine cyl- 130

inder and piston and a low pressure engine cylinder and piston, of means controlled by the movement of the high pressure piston and operated upon failure of the low pressure piston to complete its stroke simultaneously with the high pressure piston for supplying live steam to the low pressure piston.

4. In a compound pumping engine, the combination with a high pressure engine cylinder and piston and a low pressure engine cylinder and piston, of a valve mechanism adapted to normally supply live steam to the high pressure piston and exhaust steam from the high pressure piston to the low pressure piston when the pistons are stroking simultaneously and having means for supplying live steam to the low pressure piston upon completion of the high pressure piston stroke in advance of the completion of the low pressure piston stroke.

5. In a compound pumping engine, the combination with a high pressure engine cylinder and piston and a low pressure engine cylinder and piston, of a main steam distribution valve for supplying live steam to the high pressure piston and exhaust steam from the high pressure piston to the low pressure piston, a reversing valve operated by each piston for conjointly controlling the movement of the steam distribution valve, and means controlled by the high pressure reversing valve for supplying live steam to the low pressure piston upon movement of the high pressure piston to complete its stroke ahead of the low pressure piston.

6. In a compound pumping engine, the combination with a high pressure engine cylinder and piston and a low pressure engine cylinder and piston, of means operated upon movement of the low pressure piston to the end of its stroke in advance of the high pressure piston for opening a direct exhaust to the low pressure piston.

7. In a compound pumping engine, the combination with a high pressure engine cylinder and piston and a low pressure engine cylinder and piston, of means for supplying exhaust steam from the high pressure piston to the low pressure piston and adapted upon movement of the low pressure piston to the end of its stroke in advance of the high pressure piston to open a direct exhaust for relieving the pistons of exhaust steam pressure.

8. In a compound pumping engine, the combination with a high pressure engine cylinder and piston and a low pressure engine cylinder and piston, of means for supplying exhaust steam from the high pressure piston to the low pressure piston and adapted

upon movement of the low pressure piston to the end of its stroke in advance of the high pressure piston to open a direct exhaust for 65 relieving the pistons of exhaust steam pressure, said direct exhaust being closed by the movement of the high pressure piston to the end of its stroke.

9. In a compound pumping engine, the combination with a high pressure engine cylinder and piston and a low pressure engine cylinder and piston, of a main steam distribution valve for normally supplying live steam to the high pressure piston, exhaust steam from the high pressure piston to the low pressure piston, and for finally exhausting steam from the low pressure piston and a reversing valve operated by each piston for conjointly controlling the movement 75 of the steam distribution valve, the movement of the low pressure reversing valve in advance of the high pressure reversing valve being adapted to open a direct exhaust for 80 relieving the pistons of the pressure of the exhaust steam supplied to operate the low pressure piston.

10. In a compound pumping engine, the combination with a high pressure engine cylinder and piston and a low pressure engine cylinder and piston, of means controlled by the simultaneous movement of both pistons to the end of their respective strokes in one direction for supplying exhaust steam from the high pressure piston to the low pressure 95 piston and for releasing said exhaust steam at the end of the strokes in the opposite direction, communication being opened for directly releasing said exhaust steam upon movement of the low pressure piston to the 100 end of its stroke ahead of the high pressure piston.

11. In a compound pumping engine, the combination with a high pressure engine cylinder and piston and a low pressure engine cylinder and piston, of a reversing valve operated by each piston and a main distribution valve operated upon the simultaneous movement of both reversing valves for venting exhaust steam supplied from the high 110 pressure piston to the low pressure piston, the movement of the low pressure reversing valve by the low pressure piston in advance of the movement of the high pressure reversing valve being adapted to open a direct exhaust for 115 relieving the pistons of exhaust steam.

In testimony whereof I have hereunto set my hand.

WALTER V. TURNER.
